REDUCTION OF PETROLEUM NITROGEN BASES

John T. Rutherford, Berkeley, Calif., assignor to
Standard Oil Company of California, San Francisco, Calif., a corporation of Delaware

No Drawing. Application December 18, 1939,
Serial No. 309,829

10 Claims. (Cl. 260—283)

This invention relates to the reduction of certain nitrogen bases which occur in and are recoverable from petroleum naphtha distillates. More particularly, it relates to the preparation of secondary amines from the said petroleum nitrogen bases, by subjecting the bases to a controlled hydrogenation in the presence of sulfactive hydrogenation catalysts, and separating the hydrogenated from the unhydrogenated products of reaction.

Although the existence of nitrogen bases in crude petroleums and their cracked and uncracked products has long since been ascertained, and although they have indeed been separated from the hydrocarbon oils which they accompany, in many refinery oil purification operations, the bases themselves have not heretofore found any extensive use in the arts and industries, in part because they are tertiary and weakly basic in character and in part because they are made up of numerous members of homologous series rather than of a few individuals capable of easy separation. It has recently been found, however, that the corresponding secondary amines, prepared by suitable reducing methods, and various of the derivatives of the said secondary amines, are of great utility in the arts and industries, as they are stable, soluble in many organic solvents, and are strongly basic in character.

It is accordingly a purpose of the invention to disclose and provide methods of reducing petroleum nitrogen bases to their corresponding secondary amines and of separating the reduced from the unreduced nitrogen compounds and from neutral oil. Other objects and advantages of the invention will be apparent to those skilled in the art from a detailed discussion of the steps, conditions and elements embraced by the process thereof.

In the process, a crude nitrogen base-containing petroleum distillate of gasoline, naphtha or kerosene character, cracked or uncracked, is extracted with a dilute mineral acid to form water-soluble salts of mixed nitrogen bases. These salts, in aqueous acid solution, are separated from the oils which had originally accompanied the bases, and are converted to and recovered as crude bases by neutralization of the aqueous acid solution. The crude bases are then subjected to hydrogenation in the presence of a sulfactive hydrogenation catalyst, at elevated temperature and pressure and in the presence of an active sulfur carrier, to form the corresponding secondary amines. Finally, the produced secondary

amines are separated from tertiary (unchanged) amines and produced hydrocarbon oils by careful adjustment of hydrogen ion concentration. The unreduced bases are freed from hydrocarbons and returned to the hydrogenation system for substantially complete conversion to secondary amines.

The following exemplary procedures will illustrate the process of the invention in its detailed aspects.

A crude cracked naphtha, as obtained in the pyrolytic cracking of a nitrogen-containing crude petroleum oil or distillate, is extracted at ordinary temperatures with a dilute aqueous sulfuric acid solution, of a concentration generally below about 50% H_2SO_4 and preferably about 30% H_2SO_4 ; water-soluble sulfates of mixed petroleum nitrogen bases are formed. The aqueous solution of these salts is separated from the petroleum oil, by decantation, and the mixed petroleum nitrogen bases are recovered by decomposing the salts with a dilute aqueous alkali metal hydroxide solution, added to the dilute sulfuric acid solution of the basic salts in slight excess; the bases thus recovered are sufficiently water-insoluble to permit of stratification and decantation. In a typical case, a mixture of the crude bases thus separated from a crude cracked 100°—500° F. naphtha of California petroleum origin had a specific gravity of 0.943, a basic dissociation constant of 4.0×10^{-8} , an average molecular weight of 150, and an A. S. T. M. distillation boiling point range (Method D-86) between 360° and 478° F. (20% point, 382°; 50% point, 398°; 90% point, 442° F.); it had a sulfur content of 0.15% and was 99% soluble in an equal volume of 30% sulfuric acid.

The mixed nitrogen bases thus recovered are reduced to secondary amines by passage over 40 molybdenum sulfide, MoS_2 , suitably deposited on activated charcoal, in the presence of hydrogen and at superatmospheric temperature and pressure, accompanied by an active sulfur carrier such as carbon disulfide. In the above typical case, the crude mixed nitrogen bases referred to were passed over the catalyst at a rate of 0.3 volume of liquid bases/volume of catalyst space/hour at an average catalyst temperature of 505° F., accompanied by hydrogen fed at the rate of 33 moles/mol of bases and also accompanied by carbon disulfide fed at the rate of 1% by weight of the bases; the catalyst chamber was maintained at 3000 pounds per square inch hydrogen pressure. After condensation and cooling, the whole reaction mixture is adjusted

to a pH of approximately 9.5 by the careful addition of dilute aqueous sulfuric acid solution, upon which the reduced bases pass into aqueous solution as salts and the unreduced bases and produced neutral oil remain water-insoluble. The two layers thus formed are separated by decantation and dilute aqueous alkali metal hydroxide solution is added to the aqueous solution of the reduced salts, thus converting them to secondary amines which are sufficiently water-insoluble to permit of stratification and removal by decantation. In the above typical case, 56% by weight of the mixed bases were recovered as secondary amines, 36% were recovered as unreduced bases, and 8% were recovered as hydrocarbon oil. The characteristics of the secondary amines were: specific gravity, 0.849; basic dissociation constant, 1.0×10^{-3} ; average molecular weight, 146; A. S. T. M. distillation boiling point range, 340°-412° F. (20% point, 360°; 50% point, 366°; 90% point, 386° F.); solubility in 30% sulfuric acid, 100%.

In further exemplification of the several operating variables in the process as described:

The temperature of reduction is best maintained at between about 475° and about 535° F.; 500°-510° is optimum. At lower temperatures, conversion is incomplete; the table, based on operations conducted upon crude bases extracted from cracked petroleum naphtha, indicates that at higher temperatures the nitrogen base heterocyclic nucleus is destroyed, yielding large amounts of hydrocarbons (and ammonia):

Maximum oven temperature	Average oven temperature	Reduced bases	Unreduced bases	Oil
		Per cent	Per cent	Per cent
514	482	43	50	7
535	505	56	37	7
603	560	38.5	42.5	19
660	613	45	5	50

In general, increased hydrogen pressure improves the rate and degree of reduction, and a low space rate (volume liquid bases/volume catalyst/hour) is in most cases preferable. Best results are obtained when feeding about ten times the theoretically required proportions of hydrogen, that is, when feeding about 30 moles hydrogen per mol of cracked petroleum nitrogen base rather than the theoretically required 3 moles per mol, and when feeding up to about 50 moles hydrogen per mol of uncracked petroleum nitrogen base rather than the theoretically required 5 moles per mol. The table illustrates the relationships between space rate, hydrogen feed and degree of reduction, in a system maintained at 200 atmospheres hydrogen pressure and oven temperature of 505° F., in operations carried out on cracked petroleum nitrogen bases.

Space rate	Hydrogen feed		Bases reduced	Bases unreduced	Oil
	Moles/mol	Cu. ft./bbl.			
0.3	11	10,000	38	35	27
0.3	22	20,000	47	47.5	5.5
0.3	33	30,000	56	35.5	8.5

Due to the strongly basic character of the produced secondary amines and of ammonia produced in a side reaction, the continued activity of the effective hydrogenating catalysts has been ascertained as dependent upon the introduction

of an active sulfur carrier; without such addition the catalyst is progressively desulfurized, with the production of large amounts of ammonium sulfide and sulfides of the bases. Carbon disulfide in proportions from 0.5 to 1.5% by weight of the bases fed, suitably 1.0% by weight, maintains the catalyst body in active form; equivalent proportions of hydrogen sulfide may be employed in place of carbon disulfide.

The sulfactive hydrogenation catalysts referred to herein as suitable in the practice of the invention comprise the oxides and sulfides of the metals of Groups V and VI of the periodic system according to Mendeleeff, that is, of vanadium, columbium, tantalum, chromium, molybdenum, and tungsten, alone or in admixture with each other or in admixture with the oxides or sulfides of the alkali metals, the alkaline earth metals, zinc and aluminum.

As exemplified in connection with the laboratory preparation of a molybdenum sulfide catalyst: Activated carbon is immersed in a solution prepared by dissolving 235 grams of 85% molybdic acid in one liter of 15% ammonium hydroxide solution. Excess liquid is drained off and the solid is treated with hydrogen sulfide gas. Additional molybdate solution drains off during the hydrogen sulfide treatment. After absorption of H_2S is complete, the catalyst is dried in a stream of carbon dioxide. The dried catalyst is reduced for one hour with hydrogen at 600° F., at atmospheric pressure, and is then ready for use. In larger scale practice, the catalyst is sulfured in place in the reducing chamber under superatmospheric pressure and at temperatures of 500°-600° F. by recycling hydrogen with additions of carbon disulfide; under these conditions the carbon disulfide is reduced to hydrogen sulfide, which may be used directly if desired. Other suitable methods of preparing catalysts which may be employed in the practice of the invention are disclosed in the specifications of United States Letters Patent Nos. 1,894,785, 1,955,253, 2,039,259, 2,045,795, 2,100,352, 2,112,292 and 2,123,623.

A particular feature of the invention lies in the separation of reduced bases from unreduced bases and produced hydrocarbons, by the addition of a dilute mineral acid, suitably aqueous 20-30% H_2SO_4 , to the whole mixture of reduction products, until a pH of about 9.5 is reached. The aqueous solution of the salts of the reduced bases is drawn off, and dilute acid may again be added to the water-insoluble mixture of unreduced bases and oil, to further separate therefrom residual reduced bases; this extraction may be repeated if desired. The unreduced bases are then recycled to the reducing unit, either accompanied by produced hydrocarbon oil or separated therefrom by solution in excess dilute mineral acid, stratification and decantation of oil, and subsequent neutralization with dilute alkaline solution.

The process may be made continuous, throughout, by separating reduced from unreduced bases in a continuous counterflow tower and by continuously re-cycling unreduced bases, freed of hydrocarbon oils if desired, to the reducing system, together with further supplies of initial crude bases and appropriate proportions of hydrogen and active sulfur carrier.

It will be understood that the precise characteristics of the secondary amines prepared in accordance with the invention will be dependent upon the character of the cracked or uncracked petroleum oils or distillates from which the initial mixed petroleum nitrogen bases are recovered, as

well as upon the boiling point range of the distillates and the origin of the original petroleum stocks themselves. Generally, it is believed that the bases extractable from straight run or uncracked distillates are largely mixtures of alkylated quinoline homologues, while the bases extractable from the thermally cracked distillates are largely mixtures of alkylated pyridine homologues. Upon reduction in the manner hereinabove described, these bases are believed to yield mixtures of secondary amines, respectively, typified by the following structures

in which the heterocyclic nuclei are saturated and in which R represents one or more alkyl groups attached in the alpha, beta or gamma positions (probably the beta); R apparently has an average of about 5 carbon atoms per molecule, but individual members of these homologous series may carry alkyl groups containing from one to about eight carbon atoms per chain.

The secondary amines prepared in accordance with the invention are useful in the preparation of rubber vulcanization accelerators and antioxidants, as metal pickling inhibitors and as intermediates in the preparation of extreme pressure lubricating agents, insecticides, and for the numerous purposes which secondary amines of this nature serve in the arts and industries.

I claim:

1. A process of preparing a homologous mixture of heterocyclic secondary amines having a basic dissociation constant higher than 1.0×10^{-4} which comprises recovering from petroleum an initial mixture of petroleum nitrogen bases having the characteristics of tertiary amines and being substantially free of hydrocarbons and petroleum-derived impurities insoluble in an excess of 50% H_2SO_4 , subjecting the said initial mixture of petroleum nitrogen bases to the action of hydrogen under reducing conditions, at temperatures within the range 475° F. and 535° F. and at superatmospheric pressure, in the presence of a sulfactive hydrogenating catalyst comprising molybdenum sulfide and in the presence of an active sulfur carrier in proportions sufficient to prevent material desulfurization of the catalyst, and separating produced secondary amines from the normally liquid reaction mixture by adjusting the pH of the said normally liquid reaction mixture to approximately 9.5.

2. A process as in claim 1, in which the initial mixture of petroleum nitrogen bases is recovered from an uncracked nitrogen-containing petroleum distillate and is substantially free of hydrocarbons and petroleum-derived impurities insoluble in an excess of 50% H_2SO_4 , and in which the said initial mixture of petroleum nitrogen bases is subjected to the action of hydrogen in the proportions of at least 30 moles of hydrogen per average mol of bases.

3. A process as in claim 1, in which the initial mixture of petroleum nitrogen bases is recovered from a cracked nitrogen-containing petroleum distillate and is substantially free of hydrocarbons and petroleum-derived impurities insoluble in an excess of 50% H_2SO_4 , and in which the said initial mixture of petroleum nitrogen bases is subjected to the action of hydrogen in

the proportions of at least 50 moles of hydrogen per average mol of bases.

4. A process of preparing secondary amines from petroleum nitrogen bases, which petroleum nitrogen bases are substantially free of hydrocarbons and petroleum-derived impurities insoluble in an excess of 50% H_2SO_4 , which comprises passing the said petroleum nitrogen bases in vapor form through a body of sulfactive hydrogenating catalyst essentially consisting of a compound selected from the class of the oxides and sulfides of vanadium, columbium, tantalum, chromium, molybdenum and tungsten, simultaneously introducing to the catalyst body hydrogen in the proportion of at least three moles per average mol of bases, maintaining the catalyst body at a temperature within the range 475° F. and 535° F. and at superatmospheric pressure, condensing normally liquid reaction products and separating the produced secondary amines from unreduced nitrogen bases and hydrocarbon oils.

5. A process of preparing secondary amines from petroleum nitrogen bases, which petroleum nitrogen bases are substantially free of hydrocarbons and petroleum-derived impurities insoluble in an excess of 50% H_2SO_4 , which comprises passing the said petroleum nitrogen bases in vapor form through a body of sulfactive hydrogenating catalyst essentially consisting of a compound selected from the class of the oxides and sulfides of vanadium, columbium, tantalum, chromium, molybdenum and tungsten, simultaneously introducing to the catalyst body hydrogen in the proportion of at least three moles per average mol of bases, maintaining the catalyst body at a temperature within the range 475° F. and 535° F. and at superatmospheric pressure, condensing normally liquid reaction products and separating the produced secondary amines from unreduced nitrogen bases and hydrocarbon oils.

6. A process of preparing secondary amines from petroleum nitrogen bases, which petroleum nitrogen bases are substantially free of hydrocarbons and petroleum-derived impurities insoluble in an excess of 50% H_2SO_4 , which comprises passing the said petroleum nitrogen bases in vapor form through a body of sulfactive hydrogenating catalyst essentially consisting of a compound selected from the class of the oxides and sulfides of vanadium, columbium, tantalum, chromium, molybdenum and tungsten, simultaneously introducing to the catalyst body hydrogen in the proportion of at least three moles per average mol of bases and an active sulfur carrier in proportions sufficient to prevent material desulfurization of the catalyst body, maintaining the catalyst body at a temperature within the range 475° F. and 535° F. and at superatmospheric pressure, condensing normally liquid reaction products and separating the produced secondary amines from unreduced nitrogen bases and hydrocarbon oils.

7. A process of preparing secondary amines from petroleum nitrogen bases, which petroleum nitrogen bases are substantially free of hydrocarbons and petroleum-derived impurities insoluble in an excess of 50% H_2SO_4 , which comprises passing the said petroleum nitrogen bases in va-

70
75

por form through a body of sulfactive hydrogenating catalyst essentially consisting of a compound selected from the class of the oxides and sulfides of vanadium, columbium, tantalum, chromium, molybdenum and tungsten, at a space rate of approximately 0.3 volumes of liquid bases per volume catalyst body per hour, simultaneously introducing to the catalyst body hydrogen in the proportions of at least ten moles per average mol of bases and carbon disulfide in amounts between 0.5% and 1.5% of the weight of the bases, maintaining the catalyst body at superatmospheric pressure and within the range 475° to 535° F., condensing normally liquid reaction products, and separating produced secondary amines from un-reduced nitrogen bases and produced hydrocarbon oils by adjusting the pH of the normally liquid condensed reaction mixture to approximately 9.5.

8. A process as in claim 7 in which the petroleum nitrogen bases passed through the catalytic

body under reducing conditions are derived from an uncracked nitrogen-containing petroleum distillate and are substantially free of hydrocarbons and petroleum-derived impurities insoluble in an excess of 50% H₂SO₄, and in which the secondary amines ultimately recovered are largely comprised of alkylated piperidine homologues.

9. A process as in claim 7, in which the petroleum nitrogen bases passed through the catalytic body under reducing conditions are derived from a thermally cracked nitrogen-containing petroleum distillate and are substantially free of hydrocarbons and petroleum-derived impurities insoluble in an excess of 50% H₂SO₄, and in which the secondary amines ultimately recovered are largely comprised of alkylated decahydroquinoline homologues.

10. A process as in claim 7, in which the catalyst body comprises molybdenum sulfide.

JOHN T. RUTHERFORD.
